Primary Examiner — George D. Kirschbaum

Assistant Examiner — Jasmine L. Coleman

(57) **CLAIM**

The ornamental design for a transportable building as shown and described.

DESCRIPTION

1. Transportable building

1.1: Perspective

1.2: Back

1.3: Front

1.4: Right

1.5: Left

1.6: Top

1.7: Bottom

The claimed design relates to a transportable building with a pole and a propeller shown in broken lines; the broken lines represent portions of the transportable building that form no part of the claimed design.

1 Claim, 7 Drawing Sheets
